UNITED STATES PATENT OFFICE.

ALFRED C. HEATH, OF NEWARK, NEW JERSEY.

DESIGN FOR A CIGAR-LIGHTER.

42,462.

Specification for Design.

Patented May 7, 1912.

Application filed November 22, 1911. Serial No. 661,870. Term of patent 7 years.

To all whom it may concern:

Be it known that I, ALFRED C. HEATH, a citizen of the United States, and a resident of Newark, in the county of Essex and State of New Jersey, have invented a new, original, and ornamental Design for a Cigar-Lighter.

Reference is to be had to the accompanying drawing, in which the figure is a per-

spective view of a cigar lighter showing my design.

I claim:

The ornamental design for a cigar lighter, as shown.

ALFRED C. HEATH.

Witnesses:

W. S. ORTON,
PHILIP D. ROLLHAUS.
